UNITED STATES PATENT OFFICE.

JOHN MURRAY, OF NEW YORK, N. Y.

DESIGN FOR AN INKSTAND.

SPECIFICATION forming part of Design No. 13,851, dated April 10, 1883.
Application filed March 10, 1883. Term of patent 3½ years.

To all whom it may concern:

Be it known that I, JOHN MURRAY, of the city of New York, in the county of New York and State of New York, have originated a new 5 Design in Inkstands, of which the following is a full, clear, and exact description, reference being had to the accompanying drawing, making part of this specification.

My invention consists of an inkstand with a 10 base in the shape of a painter's palette, to which is attached an upright hollow cylinder. The cylinder is to be used as a receptacle for an ink-pot. To the base are affixed two projecting pieces to represent brushes, which, being upwardly flexed on the outer ends, are to 15 act as suitable rests for pen-holders or pencils.

The accompanying drawing denotes a perspective view, showing the position of my improvement and all the parts thereof.

20 In the accompanying drawing, A denotes a palette-shaped base, on which rests the cylinder D, which is fastened to the base. The cylinder D, being hollow, admits a glass or other ink-well, E. To the palette-shaped base

are affixed two projecting pieces, B B', to represent artists' brushes. The ends of the brushes extend over the edge of the base, and are upwardly flexed, so as to make a secure resting-place for pen-holders or pencils.

D' represents a cover to place over the cylinder when the inkstand is not in use.

I claim—

1. In a design for an inkstand, an artist's palette, A, and cylinder D, with the cover D', in combination with the brush-shaped pen-rack B B'.

2. In a design for an inkstand, the palette A, the cylinder D, and the pen-rack B B' integral therewith, in combination with a glass or other receptacle, E, for holding ink.

Signed at city of New York, in the county of New York and State of New York, this 8th day of March, A. D. 1883.

JOHN MURRAY.
